UNITED STATES PATENT OFFICE.

STEPHEN HIPKINS, JR., OF BELLAIRE, OHIO, ASSIGNOR TO THE BELMONT
GLASS WORKS, OF SAME PLACE.

DESIGN FOR ORNAMENTING GLASSWARE.

Specification forming part of Design No. 3,972, dated April 12, 1870.

To all whom it may concern:

Be it known that I, STEPHEN HIPKINS, Jr., of Bellaire, in the county of Belmont and State of Ohio, have invented and produced a new and original Design for Ornamenting Glassware, of which the following is a full and clear description.

The accompanying drawing represents a glass vase which is ornamented around the bowl portion H and cover I with a waved or crooked vine, K, having branches with leaves C and berries B, the whole representing a dewberry-vine with its leaves and fruit, as embraced within the red lines a b c d.

The leaves and fruit may be omitted on the upper side of the vine K, as at D, when the dish or vessel is shallow.

Having thus described my design, what I claim is—

The design for ornamenting glassware, as shown and described.

STEPHEN HIPKINS, JR.
